UNITED STATES PATENT OFFICE.

JOSEPH N. MAHONEY, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRICAL PROTECTIVE DEVICE.

1,287,721.

Specification of Letters Patent. Patented Dec. 17, 1918.

Application filed July 3, 1916. Serial No. 107,309.

To all whom it may concern:

Be it known that I, JOSEPH N. MAHONEY, a citizen of the United States, and a resident of Wilkinsburg, in the county of Allegheny 5 and State of Pennsylvania, have invented a new and useful Improvement in Electrical Protective Devices, of which the following is a specification.

My invention relates to electrical protective devices and particularly to relay mechanisms that are employed for tripping circuit interrupters upon the occurrence of predetermined circuit conditions.

One object of my invention is to provide 15 a simple and economical relay system of the character indicated that may be operated by current derived from the circuit in connection with which the interrupter is employed, thereby obviating the necessity of 20 employing a separate source of energy for supplying the operating current for its trip coil.

Another object of my invention is to provide 25 a system of the above indicated character that shall have means for connecting the trip coil in operative relation to the main circuit only when the relay has functioned properly.

The usual method of supplying a trip coil 30 with energy from the circuit to which its interrupter is connected is to cause the relay contact members to serve as the separable terminals of a shunt connection that is connected across the terminals of the trip coil. 35 However, with this arrangement, it has been found that frequently, upon the occurrence of an overload, because of imperfect contacts, the interrupter tripped before the relay functioned properly. In view of this, I 40 provide means whereby the trip coil is switched into the circuit by an electromagnetic device that is controlled by the relay, and I provide also means for maintaining a substantially constant potential across the 45 electromagnetic device after the relay operates.

The single figure of the accompanying drawing is a diagrammatic view of a distributing system embodying my invention.

An electric circuit 1 is provided with an 50 interrupter 2 having a trip coil 3 and a series transformer 4 that is adapted to supply the trip coil 3 with energy. A relay 5, comprising a magnetizable core member 6, 55 windings 7 and 8, an armature 9 and contact members 10 and 11, is adapted to be so

connected to the transformer 4 that it is responsive to predetermined conditions in the circuit 1. That is, it may be adapted to operate upon the occurrence of an overload 60 or the reversal of energy in the circuit 1 and may be delayed or not in its time of operation.

One terminal of the winding 8 of the relay 5 is connected to one terminal of the 65 transformer 4 and its other terminal is connected to one terminal of a reactor 12 and to the movable contact member 11. The other terminal of the reactor 12 is connected to one terminal of the winding 13 of an electro- 70 magnetically operated switch 14 the other terminal of which is connected to the stationary contact member 10. The terminal of the winding 13 that is connected to the reactor 12 is also connected to a movable 75 contact member 15 which is adapted to be actuated by the movable member 16 of the switch 14. The movable contact member 15 is adapted to engage two stationary contact members 17 and 18 and is of such form and 80 dimensions as to bridge the gap between them as it is moved from the one to the other. The stationary contact member 17 is operatively connected to one terminal of the transformer 4 and to one terminal of the 85 winding of the trip coil 3, the other terminal of which is connected to the stationary contact member 18.

Under normal conditions, current proportional to the current that traverses the circuit 1 traverses the winding 8 of the relay 5, the reactor 12 and contact members 15 and 17. This current is not sufficient to operate the relay 5, but, when an overload 90 traverses the circuit 1, sufficient current 95 traverses the winding 8 to effect engagement of the contact members 10 and 11. This permits current to traverse the winding 13 of the switch 14, thus causing the movable contact member 15 to engage the stationary 100 contact member 18. When the contact members 15 and 18 are in engagement, the trip coil 3 is connected in series relation with the transformer 4 and the windings 8 and 13. Thus, current proportional to the current 105 traversing the circuit 1 will traverse the trip coil 3 from the circuit to cause the interrupter 2 to be tripped.

The reactor 12 is provided with a core member 19 that is adapted to become saturated when a current of greater volume than that required to operate the switch 14 trav-

erses the circuit, and, consequently, the reactor 12 serves as a shunt connection across the terminals of the winding 13 for the purpose of maintaining a constant potential thereacross after the relay 5 has functioned. When the circuit interrupter 2 opens, no current will traverse the winding 8 and, consequently, the contact members 10 and 11 will be disengaged, the movable contact member 15 of the switch 14 will move into engagement with the stationary contact member 17 and the devices will be in their operative positions when the circuit interrupter 2 is again closed.

15 I do not limit my invention to the particular arrangement and devices illustrated, as it may be variously modified without departing from the spirit and scope of the invention, as set forth in the appended claims.

20 I claim as my invention:

1. In an electric circuit, the combination with a circuit interrupter and a normally open-circuited trip coil therefor, of a relay operatively connected to the circuit, a magnetically operated switch controlled by the relay for connecting the trip coil in operative relation to the circuit, and means for causing the potential across the winding of said switch to remain substantially constant when it is energized.

25 2. In an electric circuit, the combination with a circuit interrupter and a normally open-circuited trip coil therefor, of a relay operatively connected to the circuit, and electromagnetic means connected in series with the winding of the relay for connecting the trip coil in series with the winding of the relay without open circuiting the relay winding and a reactor for maintaining 30 the potential across the electromagnetic means constant when the relay operates.

35 3. In an electric circuit, the combination with a circuit interrupter and a trip coil therefor, of a relay operatively connected to the circuit, an electromagnetic device controlled by the relay for connecting the trip

coil in series with the relay, and means for maintaining the potential across the electromagnetic device substantially constant when it is energized.

4. In an electric circuit, the combination with a circuit interrupter and a trip coil therefor, of a relay operatively connected to the circuit, an electromagnetic device adapted to be connected in series with the relay 55 when it operates and adapted to connect the trip coil also in series with the relay, and means for maintaining the potential across the electromagnetic device substantially constant when it is energized.

5. In an electric circuit, the combination with a circuit interrupter and a trip coil therefor, of a relay operatively connected to the circuit, an electromagnetic device adapted to be connected in series with the relay 60 when it operates and adapted to connect the trip coil also in series with the relay, and means for maintaining the potential across the electromagnetic device substantially constant after the relay operates.

6. In an electric circuit, the combination with a circuit interrupter and a trip coil therefor, of a relay operatively connected to the circuit, an electromagnetic device controlled by the relay for connecting the trip 75 coil in series with the relay, and an impedance device for causing the potential across the electromagnetic device to be substantially constant when it is energized.

7. In an electric circuit, the combination 80 with a circuit interrupter and a trip coil therefor, of a relay operatively connected to the circuit, an electromagnetic device controlled by the relay for connecting the trip coil in series with the relay, and an impedance device for causing the potential across the electromagnetic device to be substantially constant after the relay operates.

In testimony whereof, I have hereunto subscribed my name this 15th day of June, 90 1916.

JOSEPH N. MAHONEY.
